THREE-DIMENSIONAL GAMEBOARD

Madelyn Tucker, 921 SW. 21st St., Fort Lauderdale, Fla.

Filed July 31, 1964, Ser. No. 81,085

Term of patent 14 years

(Cl. D34—5)

FIG. 1

FIG. 2

FIG. 1 is a perspective view of the three-dimensional gameboard showing my new design; and

FIG. 2 is a cross-sectional view of said device taken along lines 2—2 of FIG. 1; and

FIG. 3 is a front elevational view, partially in cross section, of said device taken along lines 3—3 of FIG. 1.

I claim:

The ornamental design for three-dimensional gameboard, substantially as shown.
